(57) **CLAIM**

The ornamental design for a webbing strap as shown and described.

DESCRIPTION

FIG. 1 is a front elevational view thereof;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The webbing strap is shown with symbolic breaks in its length and the appearance of any portion of the webbing strap between the break lines form no part of the claimed design.

1 Claim, 6 Drawing Sheets
